(57) CLAIM

The ornamental design for a chandelier arm, as shown and described.

DESCRIPTION

FIG. 1 is a left side view of the chandelier arm with a star-shaped surface ornament thereon and beads within a frame thereof shown in phantom, the right side view being a mirror image of the left side view;

FIG. 2 is a front view thereof;

FIG. 3 is a bottom view thereof;

FIG. 4 is a top view thereof;

FIG. 5 is a rear view thereof;

FIG. 6 is a side, front, perspective view of the chandelier arm shown attached to a chandelier, with all elements of the chandelier but for the arm shown in phantom; and,

FIG. 7 is side, front, perspective view of the chandelier arm shown attached to a chandelier, with all elements of the chandelier including four other arms, but for the one arm and beads located therein, shown in phantom.

The phantom line environmental showing is for illustrative purposes only and forms no part of the claimed design.
